JOHN H. GLEIM, OF ST. LOUIS, MISSOURI.

Letters Patent No. 83,276, dated October 20, 1868.

IMPROVEMENT IN BINDING MERCANTILE BOOKS.

The Schedule referred to in these Letters Patent and making part of the same.

To all whom it may concern:

Be it known that I, JOHN H. GLEIM, of St. Louis, in the county of St. Louis, and State of Missouri, have invented a new and useful Improvement in Book for Book-Keeping; and I do hereby declare that the following is a full, clear, and exact description thereof, which will enable those skilled in the art to make and use the same, reference being had to the accompanying drawings, forming a part of this specification.

Figure 1, Sheet I, represents my improved book open.

Figure 2, Sheet II, is a perspective view of the same, representing the copying, sales, or bill-book closed, and the journal open.

Similar letters of reference indicate corresponding parts.

My invention has for its object to diminish the number of books required in conducting a business, whether wholesale, retail, or commission, and at the same time so combining and arranging the columns of the journal as to require less labor in making the entries, and generally simplify the record of the business.

And it consists in connecting together, as shown, the copying, bill, or sales-book and journal, and the combination and arrangement of the entry-columns and blank pages in the journal, as hereinafter more fully described.

A represents an ordinary press-copying book, the lower cover of which is extended, so as to form the lower cover of the journal or balance-book B, the leaves and top covers of each closing down towards each other, as shown in figs. 1 and 2.

The book A is used for copying bills and other necessary matters, in the same manner as an ordinary press-copying book, except that the regular charges of merchandise should be copied upon the right-hand pages, and the irregular entries should be copied upon the left-hand pages, as illustrated in fig. 1, to enable the said regular and irregular entries to be readily distinguished from each other, and at the same time to guard against mistakes and errors.

In the journal B, the left-hand pages are ruled into columns, b^1 , b^2 , b^3 , b^4 , b^5 , as shown in figs. 1 and 2, but the right-hand pages are left blank, and are intended for miscellaneous entries, balances, memoranda, &c., and should be ruled by the clerk as required.

Columns b^1 are devoted to marginal entries, such as "forward," "paid," "folios," &c.

Column b^2 is a space devoted to making entries, double or single, as the case may be.

Column b^3 is designed to show the folios of the ledger to which the entries have been posted, and also enables the entries taken from the invoice or cash-books, and which have been posted from said invoice or cash-

books, to be marked, so that they may not be accidentally posted again.

Column b^4 , headed "miscellaneous," is designed for the reception of the amounts of the irregular entries, whether debit or credit, as illustrated in fig. 1.

Column b^5 is designed for the credits of merchandise only, the same being debited to the customers, and the amounts being taken from the copying-bill book A.

The posting of column b^5 , at the end of the week, is to go to credit of merchandise in the ledger.

Among the peculiar advantages of my invention may be mentioned that it obviates the necessity for the use of the ordinary journal, which is now used where copying-bill books are in use.

In using my invention, the bill-maker, upon copying the bill in book A, enters it by single entry in book B.

Debits and credits are brought to journal B, by single entry, from the invoice and cash-books, from which books they have been posted to the ledger by double entry.

The journal B, that is, the entries upon the left-hand pages, and the balances upon the right-hand pages, serve as a corrector for the ledger, while at the same time the ledger serves as a corrector for journal B, that is to say, as far as customers' accounts are concerned. In fact, there would be no difficulty in an active business, if the ledger were not used for customers, as the entries upon the left-hand pages of journal B, and the balances upon the right-hand pages of said book, will show the original entries of the account and its balance correctly.

By this invention the labor of keeping the accounts will be greatly diminished, and the labor and delay of taking the trial-balances will be much relieved, the accounts of the business being kept more compact, and being thus much easier for supervision.

The blank right-hand pages of journal B enable the merchant to record the profits of his sales. By thus extending or carrying out his profits, many advantages are gained, as, for instance, in questions of insurance, as a guide in purchasing goods, as a means of easily acquiring a knowledge of the amount of stock on hand, &c., &c.

Having thus described my invention, What I claim as new, and desire to secure by Letters Patent, is—

The combination of a journal or entry-book, B, with the press-copying book A, into one volume, substantially as herein shown and described, and for the purposes set forth.
